UNITED STATES PATENT OFFICE.

PHILIP McHALE, OF NEW BEDFORD, MASSACHUSETTS.

DRAWING-ROLL FOR DRAWING AND EVENING MACHINES.

1,091,366.

Specification of Letters Patent. Patented Mar. 24, 1914.

Application filed January 3, 1913. Serial No. 740,045.

To all whom it may concern:

Be it known that I, PHILIP McHALE, a citizen of the United States, residing at New Bedford, in the county of Bristol and State of Massachusetts, have invented new and useful Improvements in Drawing-Rolls for Drawing and Evening Machines, of which the following is a specification.

This invention relates to improvements in the construction of drawing rolls for drawing and evening machines, and particularly to a novel construction of top drawing roll, whereby the rolls are adapted to compensate for variations in the weight or thickness of the cotton sliver, and to vary their drawing or feeding action, to secure an even and regulated feed of the material.

The object of the invention is to provide a top drawing roller for machines of the character described, whereby the said roller is adapted to have movement relative to the lower drawing roller to the same or varying degrees throughout its length as occasion may require, to vary the feeding pressure according to the weight or thickness of different portions of the sliver being acted upon.

The invention consists of the features of construction, combination and arrangement of parts hereinafter fully described and claimed, reference being had to the accompanying drawings, in which:—

Figure 1 is a sectional elevation of a portion of a drawing and evening machine, showing the application of my invention. Fig. 2 is a rear elevation, partly in section, of the same. Fig. 3 is a vertical longitudinal section, on an enlarged scale, through a portion of the upper drawing roll. Fig. 4 is a vertical transverse section of the same on the line 4—4 of Fig. 3. Fig. 5 is a detail view of the members of one of the sectional bushings. Fig. 6 is a detail view of one of the roll sections.

Referring to the drawings, 1 designates the frame of a drawing and evening machine, of any preferred type, 2 the lower fluted feeding or drawing roll, which may be of any suitable construction, and 3 the upper fluted or drawing roll, constructed in accordance with my invention.

The roll 3 comprises a shaft 4, on the ends of which are fitted sleeves 5 fixed to the shaft by set screws 6 and having outer angular end portions 7 engaging suitable sockets or openings in the frame structure.

Arranged upon the shaft 4 adjacent to the respective sleeves 5 are spacing collars 8, and mounted upon the shaft between the spacing collars is a roll proper comprising a series of cylindrical roll sections 9 of greater diameter than the shaft, and each having the usual fluted periphery 10 to engage the cotton.

Each fluted roll section 9, of which any suitable number may be employed, is held in spaced relation to the shaft by a sectional bushing composed of a pair of semi-circular bushing members 11 and 12. The two bushing members are provided with guiding and retaining pins or projections 13 and 14, the pin 13 being movable within the upper portion of a transverse opening 15 in the shaft, the lower portion of which receives the pin 14 of the bushing member 12. As shown, the said lower portion of the opening 15 is enlarged to receive a coiled cushioning spring 16 surrounding the pin 14 and bearing against the bushing member 12. In practice, the bushing members are preferably made of a suitable lubricating metal, so that the roll sections 9 may freely turn thereon with a minimum degree of friction, and without the necessity of using a lubricant. For the purpose, of reducing friction to a minimum degree, the inner periphery of each roll section is provided with bearing ribs, which may be in the form of a thread, thus reducing its service contact with the bushing.

From the foregoing description, it will be understood that in the operation of the machine, the upper drawing roll as a whole may not only move vertically with relation to the lower drawing roll, but each of its sections 9 is permitted to have independent motion with relation to the drawing roll whereby the rolls are adapted to accommodate themselves to variations in the weight or thickness of the cotton sliver and to regulate their feeding action to secure an evenness of feed. Normally, of course, the back springs force the roll sections 9 toward the lower drawing roll and hold the lower bushing section spaced from the stationary shaft, while permitting the roll section to yield upwardly to a greater or less degree according to the weight or thickness of the portion of the cotton sliver with which it is in contact. By this means the upper roll is adapted to accommodate itself instantaneously and automatically to variations in

the thickness of the material, the advantages of which will be apparent.

I claim:—

1. A drawing roll, including a shaft, a roll proper consisting of a series of cylinders loosely surrounding said shaft, sectional bushings surrounding the shaft within the cylinders, each of said cylinders having a ribbed surface turning in contact with its bushings, and resilient means associated with said bushings to independently and yieldingly back said cylinders.
2. A drawing roll, including a shaft having a series of transverse apertures, each aperture enlarged at one end to form a socket, a roll proper consisting of a series of cylinders loosely surrounding the shaft, a bushing comprising guided sections arranged within each cylinder, one section of each bushing having a guide pin projecting into the smaller portion of the adjacent transverse opening in the shaft and the other section of the bushing having a pin

projecting into the socketed end of the said transverse opening, and a coiled spring associated with each bushing, each spring being arranged within the adjacent sockets and surrounding the latter named pin and bearing against the second-named bushing section, said springs co-acting with the bushings to back the cylinders.

3. A drawing roll including a shaft, a roll proper consisting of a series of cylinders loosely surrounding the shaft, sectional bushings surrounding the shaft, one for each cylinder, and springs coacting with said bushings to yieldingly back the cylinders, each of said cylinders having a ribbed surface turning in contact with its bushing.

In testimony whereof I affix my signature in presence of two witnesses.

PHILIP McHALE.
